G. FUSSNER

ELECTROMAGNETIC APPARATUS

Filed Nov. 18, 1921

UNITED STATES PATENT OFFICE.

GEORGE FUSSNER, OF MENOMINEE, MICHIGAN, ASSIGNOR TO SIGNAL ELECTRIC MFG. CO., A CORPORATION OF MICHIGAN.

ELECTROMAGNETIC APPARATUS.

Application filed November 18, 1921. Serial No. 516,046.

My present invention relates to electromagnetic apparatus and with regard to the more specific features thereof to relays for transmitting a signal concurrently to a plurality of stations.

An object of the invention is to provide a construction for the above purpose, which shall be particularly simple, rugged and inexpensive.

10 Another object is to provide a compact apparatus of the above type, in which a substantial number of separate circuits can be reliably controlled concurrently without the likelihood of mechanical or electrical interference between conductors or circuits.

The invention is applicable to fire and burglar alarm, factory call, and other signalling systems, and, in general, to systems of that type in which a signal is to be currently transmitted to a plurality of stations.

According to a feature of the invention, the armature of a single electromagnetic relay concurrently controls the circuits to all of the stations. Preferably the armature carries a plurality of electrical contactor elements for engagement and disengagement with contacts carried by a stationary insulating support. In the specific and preferred embodiment shown, the stationary contacts with associated binding posts are carried by an insulating plate which is, in turn, mounted upon the coil structure. The contactors carried upon the armature are preferably bridging contact blades each to close circuit between two or more of the binding posts, in order to connect a source of electricity with one or more signal registering or indicating instruments at different stations.

According to another feature of the invention, the insulating plate that carries the contacts is preferably fitted over the end of the magnetic core structure, projecting beyond the coil, so that the armature may be pivoted in the same position with respect to the core as if the insulating plate were not provided, and the magnetic reluctance of the apparatus is not increased.

50 According to another feature, the insulating plate carries a back stop, spaced therefrom by a small gap to limit the separation of the armature from the coil and the back stop may carry adjusting means for

positioning the armature, or, if desired, further electrical contacts.

In the accompanying drawings in which is shown one of various possible embodiments of the several features of this invention,

Fig. 1 is a plan view,

Fig. 2 is a side elevation,

Fig. 3 is a sectional view taken along the line 3—3 of Fig. 2,

Fig. 4 is an end elevation,

Fig. 5 is a detail view partly in section of one of the electromagnets and associated parts, and;

Fig. 6 is a diagrammatic view of circuits.

Similar reference characters refer to similar parts throughout the several views of the drawings.

This invention has certain features in common with that of my copending application, Serial No. 394,487, filed July 7th, 1920, in which is claimed the subject-matter common to the two inventions.

Referring now to the drawings, there is shown a base 1 preferably of wood mounted upon a metallic supporting frame 2. A stamped or sheet brass standard 3 has a foot 4 secured to the base by screws as at 5, and an upstanding leg 6 to which the electromagnet unit 7 is secured with its axis extending parallel to the base. The unit 7 preferably comprises a magnetic cross-bar or piece 8 centrally secured to the upstanding leg 6 of the standard preferably by a pair of screws 9. To the cross-bar 8 are secured preferably by screws as at 10 and in parallel relation, the magnetic cores 11. The electromagnetic coils or solenoids 12 encircle the cores with the insulating disks 13 at one end thereof against the cross-piece 8. The cores project at their free ends for the usual small distance as at 14 beyond the opposite disks 13' on the solenoids.

A generally rectangular insulating plate 15 is carried upon the coil structure, openings 16 in said plate being frictionally fitted over the preferably knurled projecting ends 17 of the core structure. The plate 15 extends upwardly from the coils, as shown, and its corners may be rounded as at 18 near the bottom to avoid interference with adjoining parts, and is in snug contact with the end disks 13', the extreme ends of the cores extending slightly beyond the plate as

at 19. The plate 15 is thus not only firmly secured upon the cores, but in turn maintains said cores in parallelism. Upon the insulating plate and preferably at a uniform distance from base 1 is a succession, in the specific embodiment shown, five, of binding posts, 20, 21, 22, 23 and 24 extending transversely through the plate. Each post has a corresponding contact bearing the same reference numeral primed on the side of the plate more remote from the bracket 3 and upon the opposite end of each of the posts are threaded the usual binding post nuts 27 and 28. At the usual distance from the extreme ends 19 of the core, is an armature 29 mounted on pivot screws 30 in a bracket 31 that is secured to the insulating base 1. The armature includes a bar 32 to bridge the two core ends when attracted thereby.

In the specific embodiment shown, I have indicated a pair of contactors in the form of spring blade members 33 and 34 mounted upon the armature and extending upwardly therefrom. The blade member 33 is U-shaped and has two upwardly extending arms 35, each carrying a contact 36 adapted to enter into registry respectively with the contacts of two of the binding posts 23 and 24 on the insulating plate. The second spring metal blade member 34 upon the armature, has three arms 37, 38 and 39, as shown, each carrying a contact 40 for registry respectively with the three remaining contacts 20', 21' and 22' on the insulating plate. As indicated in the drawing, the spring metal member 33 is electrically insulated as at 41 from the armature and from the spring metal member 34, the latter being directly secured without intervening insulation to the armature.

The usual headed pin 42 is connected by coil spring 43 and staple 44 to the armature and through it the force by which the armature is normally urged away from the electromagnet may be adjusted. To limit the separation of the armature from the electromagnet any appropriate back stop means may be provided. In the preferred form, a small insulating plate 45 is firmly supported near the upper edge of insulating plate 15, being connected thereto by screws 46 and 47, threaded from the insulating plate and the back stop plate into opposite ends of interposed spacing sleeves 48 against which the plates are thereby clamped. Any appropriate stop studs may be provided upon the back stop member, and said studs may, if desired, function also as electrical contacts. In the specific embodiment shown, three electrical binding posts 49 identical with those on the insulating plate 15 are mounted with their contacts 49' in the path of displacement of the arms 37, 38 and 39 of spring metal blade member 34.

In the installation of the specific embodiment shown, it will be understood (see Fig. 6) that binding posts 23' and 24' are connected in a circuit including a source of electric current 50 and an electrical signal instrument 51. The circuit is normally open and when the armature is attracted by the coil, the blade member 33 will serve to bridge the contacts 23' and 24' and thus to close the circuit from the source of current to the instrument to give a signal.

Binding post 21' is preferably to be connected to a source 51 of electric current separate and distinct from that previously referred to and this in turn is connected to two signalling apparatus 52 and 53 placed in different localities and connected one to each of the binding posts 22' and 20'. As the armature 29 is attracted upon occurrence of the predetermined condition to which it is to respond, the circuit will be closed from the source of current 51, through blade member 34 to both of the signal instruments 52 and 53.

It will thus be seen that in the specific embodiment, upon the energization of the coil 7 in response to the predetermined condition, a circuit will be closed by contactor 33 through the binding posts 23' and 24' and a second circuit by contactor 34 between binding posts 20', 21' and 22'. The three signal instruments 51, 52 and 53 will thus be actuated concurrently.

In the specific embodiment shown, while the relay circuit is open, the contactor 34 is pressed against the three contacts 49' which may be connected to signal apparatus 54, if desired, in the same way as the opposite contacts 20', 21' and 22'. In that case, of course, the latter signals will be continuously given, and will be automatically interrupted upon attraction of the armature by the coil, at which time, the other signals heretofore referred to will become effective.

The spring metal contact blades will yield to appropriate extent as circuit is closed, thus assuring an effective wiping electrical contact. The contact surfaces being vertical, dust and dirt will not accumulate therein, but will drop by gravity. It is clear that the position of the binding posts may be regulated by rotation of the nuts, to adjust the length of stroke of the armature.

Obviously, instead of applying the device to the two-wire system shown, in which the armature is insulated from the ground, the device may be applied to a single-wire system, the armature and the contacts thereon being grounded, in which case, each of the plurality of binding posts could be connected to a separate and distinct signal apparatus.

It will, of course, be understood that by appropriate increase of the size of the insulating plate, any greater number of contacts and binding posts within reasonable

limits could be mounted thereon, and the contactors upon the armature could be similarly multiplied and arranged in as many or as few mutually insulated groups as desired, depending on the purpose to which the apparatus is to be applied.

In the preferred embodiment of my invention, it will be noted that the base carries merely the binding posts 56 through which the current impulse is directed to the electromagnet, the binding posts for the plurality of relay circuits being all conveniently mounted upon the insulating plate 15, which may without requiring any alteration in the dimensions of the ordinary relay base, be made of sufficient size to accommodate the desired number of binding posts. The insulating plate carrying the binding posts being mounted upon the projecting ends of the electromagnetic cores, in effect, takes up no useful space whatsoever and does not in any way affect the reluctance of the magnetic circuit, the air gap between the cores and the armature not being increased with respect to constructions in which the cores are not employed as supporting means for other elements.

It should also be noted that the electromagnetic coil could be mounted in other positions with respect to the base, that the base and coil axis could either or both be in a vertical plane, if desired, and that the invention could be carried out with a coil having but a single core. I prefer, however, the specific arrangement shown and described.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

I claim:—

1. The combination in electromagnetic apparatus, of an electromagnetic coil, a core therein projecting therebeyond, an insulating plate fitted over said core and extending laterally beyond said coil, an armature under control of said coil and adjacent the free end of said core, and coacting contact means on said insulating plate and said armature for closing an electric circuit when the armature is in one of its extreme positions.

2. The combination in electromagnetic apparatus of a pair of parallel electromagnetic coils having cores projecting therebeyond,

an insulating plate having recesses fitted over the projecting ends of said cores and tightly retained in place thereon, an armature beyond said plate and adjacent the projecting ends of said cores and coacting electrical contact means carried by said armature and said plate for closing and opening an electric circuit in response to movement of the armature.

3. The combination in electromagnetic apparatus of a base, an electromagnetic coil carried thereon, an insulating plate adjacent said coil, a pair of binding posts extending through said plate and having contacts at one side thereof, and an armature for said coil at the side of said plate adjacent said contacts, said armature carrying electrical conducting means for bridging said contacts to close a circuit through said binding posts.

4. The combination in electromagnetic apparatus of an electromagnetic coil, a magnetic core therein extending therebeyond, an insulating plate having an aperture fitted over said projecting core end, an armature adjacent said projecting core end, a pair of binding posts carried by and extending through said plate at a distance from said coil, each having a contact adjacent said armature, and a contactor carried by said armature for closing a circuit between said binding posts.

5. The combination in electromagnetic apparatus of a support, an electromagnetic coil carried by said support and extending parallel thereto, said coil having a core extending therebeyond, an insulating plate tightly fitted over said projecting core end and extending at right angles to said support, a pair of binding posts at the side of said plate adjacent said coil and at equal distance from said support, each having an associated contact at the opposite side of said plate, an armature pivoted to said support adjacent the projecting end of said core, and a U-shaped metal contactor carried by said armature for bridging the contacts when the coil is energized.

6. The combination in electromagnetic apparatus of a support, a pair of parallel coils carried by said support, each having a core extending therebeyond, an insulating plate tightly fitted over said projecting core ends and extending at right angles to said support, a plurality of binding posts at the side of said plate adjacent said coil and at equal distance from said support, each having a contact associated therewith, and a plurality of contactor elements carried by said armature and insulated with respect to each other, all said contactors being shifted by the movement of said armature toward and away from the coil for closing or opening the circuit between the associated contacts.

7. The combination in electromagnetic apparatus of a base, an electromagnetic coil

thereon having a core projecting therebeyond, an insulating plate tightly fitting over said core, a pair of binding posts mounted on said insulating plate and at substantially equal distance from said core, contacts associated with said binding posts and at the side thereof remote from said coil, an armature pivoted adjacent said plate, a U-shaped spring metal blade secured at its base to said armature and having its legs projecting therefrom to make a bridging connection between the contacts associated with said binding posts after the armature has moved upon change of current through said coil.

8. The combination in electromagnetic apparatus of a base, a standard secured thereto, an electromagnetic coil secured to said standard and extending parallel to said base, said coil having a core extending therebeyond, an insulating plate tightly fitting over said core and extending at right angles to said base, a plurality of binding posts carried by said plate and equi-distant from said base, and at the side thereof adjacent said coil, each said binding post having a contact at the side thereof remote from said coil, an armature pivoted to said base adjacent said projecting core end, a sheet metal member secured to said armature and having a plurality of tongues, a second sheet metal member secured to said armature and insulated from said first sheet metal member and having a plurality of tongues, the end of each said tongue extending into proximity of a corresponding contact, whereby upon movement of said armature by said coil, each of said spring metal members will bridge the associated contacts for effecting circuit connections.

9. The combination in electromagnetic apparatus, of a horizontal base, a standard secured thereon, an electromagnet comprising a pair of cores parallel to said base mounted upon said standard and projecting to one side thereof, solenoids surrounding said cores, an insulating plate secured to the ends of said cores remote from said standard, an armature pivoted to said base and extending adjacent the projecting ends of said cores, a plurality of binding posts carried on said plate above said electromagnet and at the side thereof adjacent said standard, each said binding post extending through said plate and having a contact at the opposite side thereof, a plurality of spring metal blades secured to said armature for coaction

with said contacts, means normally urging said armature away from said electromagnet, and back stop means carried by said plate for limiting the extent of separation. 60

10. In electromagnetic apparatus, in combination, a base, a standard supported thereon, an electromagnet comprising a pair of cores supported by said standard and extending parallel to said base, electromagnetic 65 coils encircling said cores, an insulating support plate fitted frictionally over the ends of said cores remote from said standard, a back stop plate spaced from said support plate and supported thereon near the 70 upper edge thereof, an armature pivoted to said base, contact blades carried by said armature, binding posts carried by said plate at the side thereof adjacent said coils, and contacts on said posts adjacent said blades 75 to be contacted by the latter for circuit closure.

11. The combination in electromagnetic apparatus of a base, a standard secured thereto, electromagnetic coil means supported at one end by said standard, an armature adjacent the opposite end of said coil means, and an insulating element carried by said coil means adjacent said latter end, said element having parts extending on opposite 85 sides of said armature, and a plurality of electrical contacts carried thereby.

12. The combination in a relay, of a base, a standard secured thereon, electromagnetic coil means supported at one end by said standard, an insulating support carrying a pair of contacts and in turn carried by the end of said coil means, an armature adjacent said support, and a contactor on said armature adapted to bridge said pair of contacts. 90

13. The combination in a relay of a base, a standard secured thereon, an electromagnet comprising a pair of cores parallel to said base mounted upon said standard and projecting to one side thereof, solenoids surrounding said cores, an insulating plate secured to the ends of said cores remote from said standard, a contact carried by said plate and an armature pivoted to said base 100 and having a contact for coaction with said first contact. 105

Signed at Menominee in the county of Menominee and State of Michigan this 15th day of November A. D. 1921.

GEORGE FUSSNER.
